WEBBING SUPPORT FOR UPHOLSTERY.

Application filed December 3, 1926. Serial No. 152,420.

My invention relates to articles of furniture such as sofas, settees, chairs and the like, and particularly relates to the means for sustaining the webbing with the springs imposed thereon.

The general object of my invention is to provide supporting means for the webbing which will resist the tendency of strains on the webbing from pulling out the tacks which secure the webbing to the frame of the article of furniture.

Reference is to be had to the accompanying drawings forming a part of this specification, it being understood that the drawings are merely illustrative of one example of the invention.

Figure 1 is a transverse vertical section of a sofa having my invention embodied therein.

Figure 2 is an enlarged longitudinal vertical section on the line 2—2 of Figure 1.

Figure 3 is a perspective view of the webbing supporting device shown in Figures 1 and 2.

In the illustrated example of my invention the letter A indicates a sofa; B, the seat frame thereof; C, the longitudinal strips of webbing; D, transverse webbing strips and E, the springs, all of which are shown as arranged usually.

The usual tacks which secure the webbing to the frame B are indicated at "b" in Figure 2. Wherever the springs are fastened on the webbing close to the tacks such as

"b" the strains are directly effective on the tacks and after a period of use said strains tend to pull the tacks from the frame and loosen the webbing, thereby removing the proper support from the springs.

In accordance with my invention I provide supports designated generally by the numeral 10, which in practice are of stirrup-like form comprising a cross-bar and vertical or approximately vertical arms 11. The arms 11

are adapted to be secured to the frame such

as B by transversely driven tacks or equivalent means. I have shown holes 12 in the arms 11 receiving tacks or brads 13. The supports 10 are fastened close to the frame B and secured tightly thereto, and therefore 50 said supports lie close to the ordinary tacks "b" driven vertically through the webbing at the under side of said frame B.

The form and position of the supports 10 result in said supports taking care of the vertical strains on the webbing and these strains in turn are taken up by the transverse fasteners 13, so that the tacks "b" are entirely relieved of strain.

It will be observed from Figures 2 and 3 60 that the crossbar of each stirrup-like support 10 is arched or semi-circular in cross-section, which form not only results in strengthening the support but results in presenting a rounded surface to the fabric strips C and D, so that no cutting edges can act injuriously on the fabric.

The arched crossbar of each support 10 lies directly against the under side of the fabric strips C and D.

I would state furthermore that while the illustrated examples constitute practical embodiments of my invention, I do not limit myself strictly to the exact details herein illustrated, since, manifestly the same can be considerably varied without departure from the spirit of the invention as defined in the appended claim.

What I claim is:

As an article of manufacture, a stirrup-like webbing support formed of a strip of sheet metal having a horizontal webbing-receiving broad member arched in cross section, and upright flat securing members the lower ends of which upright securing members present a twist, said twisted portions merging into the arched horizontal members.

KEGHAM BALIKJIAN.
